OPERATING HANDLE ADAPTER

John C. Brumfield, Philadelphia, Pa., assignor to I-T-E Circuit Breaker Company, Philadelphia, Pa., a corporation of Pennsylvania

Application September 10, 1952, Serial No. 308,809

4 Claims. (Cl. 209—172)

This invention relates to a closing handle adapter and more particularly is directed to an adapter for circuit breakers to convert rotational motion into straight line movement.

A vast majority of small circuit breakers are constructed in such a manner that the movement of the operating handle which accomplishes resetting and closing of the contacts, is straight line motion.

Circuit breakers of this type will have four positions of the handle, an off position, a reset position, an on position and a trip position, all of which are in straight line movement of the handle.

In commercial applications, it is frequently desirable to mount the small breakers in an enclosure housing. These enclosure housings are usually manufactured so that they may be adapted to house various types of circuit protective equipment such as switches, circuit breakers, starters, etc. Furthermore, such enclosure housings are usually adapted with handle means which have rotational movement.

Accordingly, small type circuit breakers which are controlled by straight line movement of the operating handle must be provided with adapter means to enable the rotary handle of the enclosure to impart straight line movement to the circuit breaker handle.

With the adapter of my invention, it is possible to house and control a standard type circuit breaker in a standard type enclosure.

The primary object of my invention is to provide means which will translate the rotary motion into linear motion.

Another object of my invention is to provide adapter means to enable a standard circuit breaker to be housed in a standard type enclosure containing a rotary type handle.

A still further object of my invention is to provide adapter means which will prevent the opening of the enclosure door when the circuit breaker and its handle are in the on, trip or off position.

Still another object of my invention is to provide means to be attached to a circuit breaker which is to be housed in an enclosure containing a rotary handle which permits the enclosure door to be opened when the control handle is moved to the reset position.

Another object of my invention is to provide adapter means to be used in conjunction with an escutcheon switch plate so that the switch is latched to the adapter means in the on or trip position of the handle but is released from latch position in the off and reset positions of the handle.

A still further object of my invention is to provide adapter means for circuit breakers which are to be housed in a standard enclosure which can be unlatched from the handle when the defeater means of the rotary handle is operated.

These and other objects of my invention will be apparent from the following description taken in connection with the drawings in which:

2

Figure 1 represents a cross-sectional view of the rotary handle showing its interior latched with the operating arm of the adapter means.

Figure 2 is a cross-sectional view of an enclosure rotary handle showing the position of the interior parts when the mechanism is in the latched and locked position.

Figure 3 is a cross-sectional view of a rotary handle for an enclosure cover showing the position of the interior parts when they are in an unlatched position.

Figure 4 is a bottom view of the moulded portion of the rotary switch showing the detent and recesses to receive the interior operating parts of the handle.

Figure 5 is an exploded view of the moulded handle and associated interior parts of a handle which may be used with my invention.

Figure 5a is a top view of the escutcheon plate used to control the movement of the interior parts of the rotary handle.

Figure 5b is a top view of a retainer plate which holds the interior parts of the rotary switch in proper position.

Figure 5c is an end view of the latch retainer means for the rotary switch.

Figure 6 is a perspective view of the adapter means mounted on a circuit breaker with the enclosure door in the open position.

Figure 7 is a front view of the operating plate of the adapter means.

Figure 8a is a front view of the operating arm of the adapter means.

Figure 8b is a side view of the operating arm of the adapter means.

Figure 8c is an end view of the operating arm of the adapter means.

Figure 9a is a front view of the support bracket of the adapter means.

Figure 9b is a side view of the support bracket of the adapter means.

Figure 9c is a view taken in the direction of the arrows 9c—9c of Figure 9a.

Figure 10a is a front view of the enclosure housing with the enclosure door in the closed position.

Figure 10b is a front view of the enclosure housing with the enclosure door thereof open showing the position in the small circuit breaker with the adapter means thereon.

The adapter means by which the rotational movement of the operating handle 51 is translated into straight line motion as best illustrated in the perspective view of Figure 6.

The adapter consists of three main members, a support bracket as seen in Figure 9, an operating arm as seen in Figure 8, and an operating plate as seen in Figure 7.

As best seen in Figures 6, 9a and 9b, the support bracket 10 is U-shaped member having an ear 11 extending from one leg 40 thereof. The ear 11 is provided with two openings 12 and 13 to enable the support bracket to be attached to the small circuit breaker 14.

The lower leg 15 has a groove 16 cut therein to thereby form two extending ears 17 and 18. As will hereinafter be more fully explained, the ears 17 and 18 serve a dual purpose. These ears will be positioned in the groove 19 of the small circuit breaker 14 so that when the support bracket 10 is attached by means of screws 20 and 21 extending through openings 12 and 13, the extension ears 18 and 17 will be properly seated in the handle groove 19. Thus, by this means, support bracket 10 is rigidly secured to the circuit breaker 14 and is prevented from movement with respect thereto. The ears 17 and 19 also serve as a guide for extension 41 of the operating plate 37 as will hereinafter be more fully explained.

The support bracket 10 has a pin 23 riveted to the base thereof. The reduced cross-sectional area 24 of the riveted pin 23 enables the operating arm 25 to be ro-

tatably mounted on the support bracket 10 by means of a washer cotter pin 23.

As best seen in Figure 6 and 7, the operating arm 25 has a bell crank member having extensions 26 and 27. A hole or groove 28 is located in the center thereof to enable the operating arm 25 to be rotatably mounted on the riveted pin 23 of the support bracket 10.

Extension member 29 is an integral part of the operating arm 25 formed by the bend at 29' to enable extended portion 29 to lie in a perpendicular plane to the extensions 26, 27 of the operating arm 25. As will be best seen in Figures 6 and 8b, the extension 29 is provided with a rectangular groove 30 which will be positioned to receive the latch extension ear 31 of the operating handle as will hereinafter be more fully explained.

The pin 32, with reduced cross-sectional area 33, is rigidly attached to the extending arm 27 of the operating arm 25. The pin 32 is perpendicular to the plane of the operating arm 25 and extends in a direction opposite to that of the direction of the member 29.

The operating plate 37, as best seen in Figures 6 and 7, has an extending portion 38 in which a receiving hole 39 is located. The reduced cross-sectional area 33 of the operating arm pin 32 is placed in a receiving hole 39 of the operating plate 37 and, by means of a washer cotter pin connection, the plate 37 is rotatably mounted on the arm 25. As best seen in Figure 6, the operating plate 37 will be partially positioned within the area enclosed by the legs 15, 39 and 40 of the support bracket 10.

The extending member 41 of the plate 37 will be positioned between the ears 17 and 18 of the support bracket 10 to thereby restrict its transverse motion. It will be further noted that since ears 17 and 18 are lodged in the groove 19 of the circuit breaker 14 so that the extending arm 41 is further restricted from lateral movement due to the circuit breaker 14 being on one side and the surface 42 of the member 15 being on the other side.

Thus, it will be apparent that even though the upper portion 38 of the operating plate 37 may have rotational movement, the guide means 17, 42, 18 and a portion of the circuit breaker 14 will restrict the motion of the extending arm 41 to substantially straight line motion.

The middle portion 42 of the operating plate 37 is provided with a substantial rectangular opening 43 so that the length of the pin 32 will determine the parallel placement of the operating arm 37 with respect to the circuit breaker 14.

Thus, the pin 32 is made sufficiently long so that the opening 43 of the operating plate 37 will surround the operating handle 22 of the circuit breaker 14 when the adapter is placed thereon. The control of the operating arm 25 will be transmitted through the member 29 of the operating plate 25, which in turn will result in movement of the operating plate 37.

Since the circuit breaker handle 22 is located within the opening 43 of the operating plate 37, the movement of this plate will result in the movement of the operating handle 22.

As will hereinafter be more fully explained, the rotational operating handle located on the enclosure door will latch with the groove 30 of the operating arm extension 29 and cause rotational movement of this arm.

Thus, although the extension 38 will have rotational motion imparted thereto by operating arm 25, the guide members 17 and 18 surrounding the operating plate extension 41 will restrict this member to substantially straight line motion and thus, the opening 43 of the operating plate 37 will likewise have substantial straight line motion.

Accordingly, it should now be apparent that by means of the support bracket 10, the operating arm 25 and the operating plate 37, that the rotational movement of the enclosure operating handle can be transferred to the operating plate so that motion is transferred into straight line motion.

The circuit breaker 14, with an adapter attached thereto, is placed in the housing 50, as seen in Figure 10b. A standard handle, having rotational movement, is illustrated by 51 in Figure 10a. This handle 51 has rotational movement which my invention will translate into straight line motion to thereby enable control of the circuit breaker 14 from handle 51 when the enclosure door 52 is closed, as seen in Figure 10a.

The handle 51 with which my present invention may be used will be described to illustrate how it operates and coordinates with the adapter of my invention.

The handle 51 has a moulded portion 53, as best seen in Figures 4 and 5. Grooves and recesses are located within the handle to house the operating interior parts thereof. Groove 54 of the moulded portion 53 houses spring 55 and plunger 56, as best seen in Figures 1, 2, 3 and 5. One end of the spring 55 is urged against the moulded portion 53 and the other end is urged against its support in the plunger 56 to thereby continuously bias the plunger in a downward direction. As will hereinafter be more fully explained, the extension plunger 56 will engage the flat surface of the operating arm 25 when the enclosure door 53 is closed. That is, when the enclosure door 52 is closed, the plunger 56 will be urged against the action of its biasing spring 55 to thereby remove it from a groove 73 in the escutcheon plate 68, as herein-after described.

A latch plate 57 is located within the groove 58 of the moulded handle 53. A latch retainer pin 59 is imbedded in the moulded material at 54 and has an opening 60 as best seen in Figure 5. The opening 60 surrounds the extension ear 61 of the latch plate 57 to thereby guide its movement and insure that it will be properly retained within the moulding 53.

The latch plate 57 is provided with an opening 62 to house spring 63. The left hand of the bias spring 63 is lodged against a step portion 64 of the moulding 53 and the right end thereof is lodged against the surface of the latch plate 57.

In the position shown in Figure 1, the biasing spring 63 is in a compressed position and is tending to urge the latch plate 57 to the right as shown in Figure 3. A latch actuated cam follower 65 is located in the groove 58 of the moulded portion 53 and disposed below the latch 57 as best seen in Figures 1, 2 and 3. A spring 66 is lodged between the latch 57 and the latch actuated cam follower 65 to bias this latter means forward. The lower surface of the follower 65 has a notch or groove cut therein to thereby form two cam following surfaces, namely the surface 67 to ride the inside diameter of the escutcheon plate 68 and the rear surface 69 to be cammed by the outside diameter of the escutcheon plate 68.

The configuration of the escutcheon plate 68 is best seen in Figure 5a. The plate is provided with attachment holes 69 so that it can be secured to the outer surface of the enclosure door 54. The moulded portion 53 with the interior operating mechanism heretofore described is then placed over the escutcheon plate and the entire mechanism is held in place by means of a retaining plate 70, as best seen in Figures 1, 2, 3 and 10b.

The operating handle has four positions, an on, a trip, off and a reset position, as noted by the markings on the escutcheon plate 68 of Figure 5a.

When the enclosure door 52 is in the open position, the plunger 56 will be biased to the extreme position by the biasing spring 55. In this position, the portion 72 of the plunger 56 will move downward through the opening 71 of the escutcheon plate 68 and engage the retaining plate 70.

Thus, in this position, the movement of the operating handle 51 will be restricted due to the insides of groove 71 engaging the edges of the plunger 56. This construction is provided so that the reclosing of the door 52 will insure that the handle 51 is in the proper position to

receive the extension 29 of the operating arm 8. Thus, the handle 51 can be moved between the off and reset position when the door 52 is open but cannot be moved to the trip or on position.

It should be further noted that when the handle 51 is in this reset position, the cam surface 67 of the latch actuated cam follower 65 will be urged against the portion 73 on the inside diameter of the escutcheon plate 68. Hence, the biasing spring 63 will urge the latch member 57 and its associated follower 65 to their extreme right position, as shown in Figure 3.

When the enclosure door 52 is closed, the plunger 56 will engage the flat surface of the operating arm 25 and thereby be urged against the biasing spring 55 and thus remove its portion 72 from the restriction groove 71 of the escutcheon plate 68.

Also, the closing of the door 52 will position the groove 74 of the moulding 53 around the extension 29 of operating arm 25 so that the opening 30 is located opposite the ear 31 of the latch member 57.

As heretofore noted, the removal of the plunger 56 from the groove 71 of the escutcheon 68 will permit the handle to be rotated to the "on" position. As the handle is rotated in this clockwise direction, the cam surface 67 of the latch actuated cam follower 65 will engage the smaller diameter 74 of the escutcheon plate 68. This operation will cam the follower 65 forward and thereby urge the latch member 57 forward against the action of its biasing spring 63. As best seen in Figure 1, this operation will permit the ear 31 of the latch plate 57 to engage the opening 30 of the adapter operating arm 25. Hence, the rotating handle 51 will be latched to the adapter means and will be able to impart motion thereto.

As the moulding 53 is rotated toward the "on" position, the surface 67 of the follower plate 65 will always ride on the small inside diameter 74 of the escutcheon plate to insure that the rotating handle is continuously latched to the operating arm 25 of the circuit breaker adapter means.

It will thus be apparent that the rotational motion of the moulded handle 53 will be imparted to the operating arm 25 and be converted to straight line motion by means of the mechanism heretofore described to thereby control the handle 22 of the circuit breaker 14.

It will be further noted that when the moulded handle 51 is in the "on" or "trip" position, the inside diameter of the escutcheon plate 68 will cam the follower 65 and the latch 57 to insure latch engagement between the ear 31 of the latch member 57 and the opening 30 of the operating arm 25. Hence, in this position of the moulded handle 53, it will not be possible to open the door 52 due to this latch engagement. However, it will be noted that relative movement between the latch plate 57 and follower 65 is permitted due to the difference in width between portions 94 and 95.

It is possible to defeat the latch by having the operator engage the hook 78 of the latch plate 57 and force it to the right to thereby disengage the ear 31 from the operating handle 25 and thus, place the parts in an unlatched position. Hence, when this defeater operation is used, the door 52 may be opened even though the circuit breaker 14 is in the "trip" or "on" position. However, it will be noted that to achieve such operation, it is necessary for the operator to actuate the defeater 78 and is not a normal operation of the apparatus.

The inside diameter of the escutcheon plate 68 is provided with an additional groove 88. Hence, when the defeater mechanism is used to enable the enclosure door 52 to be opened when the circuit breaker 14 is in the "on" position, the spring 55 will bias the plunger 56 into the groove 88. If the door 52 is opened when the circuit breaker 14 is in the "trip" position, rotation of the handle 51 will be restricted due to the position of the plunger 56 within this groove 88. Hence, when the defeater is re-closed, the opening 74 will be properly positioned to re-

ceive the extension 29 of operating arm 25 which will then be in a position corresponding to the "on" or "trip" position.

It will be further noted that the "reset" position of the handle 22 of the small circuit breaker 14 is not a permanent position as the handle 22 will always be biased from the "reset" to the "off" position. That is, it is necessary for the operator to continuously exert the force on the circuit breaker handle 22 if it is to be maintained in the reset position.

It has been found undesirable to permit the door 52 to be opened when the operating handle of the circuit breaker is in the "off" position. That is, if additional means are not provided, due to the unlatching of the rotational handle 51 from the operating arm 25 when the parts are in an "off" position, a shock force could easily open the door 51. This undesirable feature is readily eliminated by providing stop means 80 on the enclosure door 52.

The means 80 has an extension arm 82 which extends parallel to the enclosure door 52. When the moulded handle is in the "off" position, the extension 26 of the operating arm 25 will be positioned behind the extension 82. Thus, even though the ear 31 of the latch plate 57 is disengaged from the opening 30 of the operating arm 25 of the adapter means, the engagement of the extension 26 with the extension 82 will prevent the enclosure door 52 from being opened.

However, when the moulded handle is temporarily moved to the "reset" position, the extension 26 will no longer be opposite the extension 82 and the door can be easily opened.

It will be noted that the escutcheon plate 68 is provided with a groove 83 in its outer diameter, as best seen in Figure 5a. Thus, when the moulded handle 53 is in the "on" position, the operator can push the extension 84 forward to the position of Figure 2 to permit a lock 85' to be placed in the groove 83. With the lock 85' to hold the follower plate 65 forward, its cam surface 69 will be latched in the groove 84 to thereby prevent rotational movement of the moulded handle 53 to thereby prevent the operator from rotating the handle to the "trip," "off" or "reset" position and also prevent the enclosure door 52 from being opened.

It should be further noted that the moulded handle 53 is provided with a groove 86 in which the bent portion 87 of the escutcheon plate 68 is located. Thus, the limit of the rotational movement of the moulded handle 53 is governed by the arc length of the groove 86 due to the engagement with the bent member 87 with the limits of the groove 86.

In the foregoing, I have described my invention only in connection with preferred embodiments thereof. Many variations and modifications of the principles of my invention within the scope of the description herein are obvious. Accordingly, I prefer to be bound not by the specific disclosure herein but only by the appending claims.

I claim:

1. An adapter for a circuit breaker to convert rotational movement of an operating handle to straight line motion of the circuit breaker handle comprising a support bracket, an operating arm and an operating plate, said support bracket being rigidly secured to said circuit breaker, said operating arm being pivotally mounted to said support bracket, said operating plate rotatably mounted on said operating arm and having its motion governed and limited to substantially linear motion by said support bracket and said circuit breaker, said operating plate having an opening therein to receive said circuit breaker handle.

2. An adapter for a circuit breaker to convert rotational movement of an operating handle to straight line motion of the circuit breaker handle comprising a support bracket, an operating arm and an operating plate, said support bracket being rigidly secured to said circuit breaker, said

operating arm being pivotally mounted to said support bracket and having a bell crank section with a perpendicular extension extending therefrom, said perpendicular extension having an opening therein to be engaged by latch means of said operating handle, said operating plate rotatably mounted on said operating arm and having its motion governed and limited to substantially linear motion by said support bracket and said circuit breaker, said operating plate having an opening therein to receive said circuit breaker handle.

3. In a circuit breaker enclosure, a circuit breaker, adapter means and an operating handle, said circuit breaker comprising a handle with straight line motion, said enclosure means comprising a housing and an enclosure door, said circuit breaker mounted in said housing, said operating handle mounted on said door, said adapter means connecting said operating handle to said circuit breaker handle when said enclosure door is in the closed position, said adapter converting rotational movement of said operating handle to straight line motion of said circuit breaker handle and comprising a support bracket, an operating arm and an operating plate, said support bracket being rigidly secured to said circuit breaker, said operating arm being pivotally mounted to said support bracket and having a bell crank section with a perpendicular extension extending therefrom, said perpendicular extension having an opening therein to be engaged by latch means of said operating handle, said operating plate rotatably mounted on said operating arm and having its motion governed and limited to substantially linear motion by said support bracket and said circuit breaker.

4. In a circuit breaker enclosure, a circuit breaker, adapter means and an operating handle, said circuit breaker comprising a handle with straight line motion, said enclosure means comprising a housing and an enclosure door, said circuit breaker mounted in said housing, said operating handle mounted on said door, said adapter means connecting said operating handle to said circuit breaker handle when said enclosure door is in the closed position, said adapter converting rotational movement of said operating handle to straight line motion of said circuit breaker handle and comprising a support bracket, an operating arm and an operating plate, said support bracket being rigidly secured to said circuit breaker, said operating arm being pivotally mounted to said support bracket and having a bell crank section with a perpendicular extension extending therefrom, said perpendicular extension having an opening therein to be engaged by latch means of said operating handle, said operating plate rotatably mounted on said operating arm and having its motion governed and limited to substantially linear motion by said support bracket and said circuit breaker, said operating plate having an opening therein to receive said circuit breaker handle.
